UNITED STATES PATENT OFFICE.

JOSEPH J. CAMYRE, OF SPRINGFIELD, MASSACHUSETTS.

DESIGN FOR A COMBINATION FLOOR LAMP AND ASH TRAY.

Application filed April 9, 1928. Serial No. 26,203. Term of patent 7 years.

To all whom it may concern:

Be it known that I, JOSEPH J. CAMYRE, a citizen of the United States, residing at Springfield, in the county of Hampden and State of Massachusetts, have invented a new, original, and ornamental Design for a Combination Floor Lamp and Ash Tray, of which the following is a specification, reference being had to the accompanying drawings forming part thereof.

The figure is a side elevational view showing my new design for combination floor lamp and ash tray.

I claim:

The ornamental design for a combination floor lamp, and ash tray, as shown.

JOSEPH J. CAMYRE.
